H. J. HINDE,
COWL DASH BLANK,
APPLICATION FILED MAY 5, 1914.

1,174,150.

Patented Mar. 7, 1916.

UNITED STATES PATENT OFFICE.

HENRY J. HINDE, OF TOLEDO, OHIO, ASSIGNOR TO TOLEDO MACHINE AND TOOL COMPANY, OF TOLEDO, OHIO.

COWL-DASH BLANK.

1,174,150.

Specification of Letters Patent. Patented Mar. 7, 1916.

Application filed May 5, 1914. Serial No. 836,511.

To all whom it may concern:

Be it known that I, HENRY J. HINDE, a citizen of the United States, residing at Toledo, in the county of Lucas and State of Ohio, have invented a new and useful Cowl-Dash Blank, of which the following is a specification.

The device forming the subject matter of this application is a cowl-dash blank and the invention aims to provide, as an article of manufacture, a cowl-dash blank embodying a removable portion of novel form adapted to act as a reinforcement during the shaping of the cowl-dash.

With the foregoing and other objects in view which will appear as the description proceeds, the invention resides in the combination and arrangement of parts and in the details of construction hereinafter described and claimed, it being understood that changes in the precise embodiment of the invention herein disclosed, can be made within the scope of what is claimed, without departing from the spirit of the invention.

In the drawings accompanying this specification and forming a part thereof, the preferred embodiment of my invention is illustrated, in which:—

Figure 1 is a perspective view of the finished cowl dash, looking from the front. Fig. 2 is a rear view in perspective of the cowl dash, illustrating the same during one of the intermediate stages of formation, the cowl dash being of that type which is formed singly and the bottom forming element or portion discarded. Fig. 3 is a bottom plan view of the cowl dash during the same stage of formation. Fig. 4 is a cross sectional view taken on the line 4—4 of Fig. 3. Fig. 5 is a cross sectional view of a stamping in which two cowl dashes are being simultaneously produced, representing the same prior to the final cutting and trimming steps.

Referring to the drawings in which similar reference numerals designate corresponding parts throughout the several views, the finished cowl as illustrated in Fig. 1 includes the side walls 4, top 5 and inwardly extending frontal flange or rim F. The bottom is entirely open as illustrated at 9, as is the usual construction of cowl dashes.

It has been the usual practice heretofore

in forming bottomless cowl dashes with open fronts, to construct the same of a plurality of sections brazed, welded or riveted together.

The present invention contemplates a process by means of which a cowl dash may be formed from a single piece of sheet metal without danger or likelihood of distortion during the several steps of drawing and stamping and with the finished article embodying a unitary structure and possessing all the advantages thereof. With this in view, a blank is first cut and includes a portion such that the cowl dash after being subjected to the shaping or drawing operations will include the full front wall 9' and bottom 6. This provides that the blank may be clamped upon all sides for the successful shaping and drawing operations. The full front wall 9' and bottom 6 provides that the cowl dash during its intermediate stages of formation as illustrated in Figs. 2, 3 and 4 will be in the form of an open ended receptacle, thus providing a rigid structure and preventing its distortion when the final stamping and cutting operation is performed.

After the blank has been stamped in the form illustrated in Figs. 2, 3 and 4, it is placed in suitable dies and the bottom 6 removed and the front wall cut along the dotted line 12 to form the frontal flange F. The dotted line in Fig. 2 corresponds to the line 12 in Fig. 1 which in that figure defines the inner limit of the said frontal flange. A rib 11 is formed in the frontal flange which braces the same and also provides a projection upon which the hood or bonnet of a vehicle may rest.

The blank 5 represents an intermediate step in the process of simultaneously forming two complete cowl dashes. The blank used in this case is sufficiently large to form two complete cowl dashes, the lower cowl dash taking the place and performing the functions of the bottom 6. The blank is interposed between suitable dies and by successively drawing is shaped as illustrated in Fig. 5. The cowl dash is then interposed between suitable dies and cut along the line 14, and at the same time the front wall 9' is removed.

The finished article as illustrated in Fig. 1, includes the rearwardly projecting ex-

tensions 7 which conform to and are adapted to engage a vehicle body. The side walls 4 and top 5 may be also curved so as to harmonize with the general appearance and complete the symmetry of a vehicle body.

Having thus described the invention, what I claim is:—

1. As an article of manufacture, a partially completed cowl-dash fashioned from a single sheet of material and comprising a top, sides, a continuous front uniting the top and the sides, and a connection uniting the sides, the connection and the front acting as reinforcements during the shaping of the dash, 15 the connection being removable, and a por-

tion of the front being removable to form a frontal flange.

2. As an article of manufacture, a partially completed cowl-dash fashioned from a single sheet of material and comprising a top, 20 sides, and a removable connection uniting the sides, the connection acting as a reinforcement during the shaping of the dash.

In testimony that I claim the foregoing as my own, I have hereto affixed my signature 25 in the presence of two witnesses.

HENRY J. HINDE.
